(57) **CLAIM**

The ornamental design for a LED stadium light as shown and described.

DESCRIPTION

FIG. 1 is a front elevational view of a LED stadium light showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front perspective view thereof;

FIG. 8 is a front perspective view of a LED stadium light in an alternate position;

FIG. 9 is a rear perspective view of the LED stadium light of FIGS. 1-6;

FIG. 10 is a rear, left perspective view of a LED stadium light in the alternate position of FIG. 8;

FIG. 11 is a rear, right perspective view thereof; and,

FIG. 12 is a rear perspective view thereof.
